Attorney, Agent, or Firm—Frijouf, Rust & Pyle

[57] CLAIM

The ornamental design for a knockdown rocking chair, as shown and described.

DESCRIPTION

FIG. 1 is a prospective view of the rocking chair showing my new design;

FIG. 2 is a front view thereof;

FIG. 3 is a top view thereof;

FIG. 4 is a bottom view thereof;

FIG. 5 is a rear view thereof;

FIG. 6 is a right-hand side view of the rocking chair with the left-hand side view being a mirror image thereof; and

FIG. 7 is an enlarged partial sectional view taken along lines 7—7 of FIG. 6 whereby to show the edge design in greater detail.

FIG. 1

FIG. 2

FIG. 3

FIG. 4

FIG. 5

FIG. 6

FIG. 7
